PIGEON CONTAINER

Otto Meyer, Wynnewood, and Lewis Stein, Philadelphia, Pa., assignors to Government of the United States of America, as represented by the Secretary of War

Application September 15, 1944, Serial No. 554,296

3 Claims. (Cl. 229—45)

(Granted under the act of March 3, 1883, as amended April 30, 1928; 370 O. G. 757)

The invention described herein may be manufactured and used by or for the Government for governmental purposes, without the payment of any royalty thereon.

This invention relates to improvements in containers for transporting and housing carrier pigeons for military purposes.

Homing pigeons have proven to be of great military value, and as a result it has been necessary to transport large numbers of pigeons to combat areas. The containers used in the transportation of the pigeons are considered as expendable inasmuch as they are used for one-way transportation only. Since these containers have heretofore been made of metal or wood, and consequently bulky, it has been inconvenient to transport them to pigeon loading depots. Also, the metal and wood is needed for more important military purposes.

It is, therefore, an object of this invention to provide a collapsible card board container for transporting carrier pigeons.

A further object is the provision of a container having a plurality of independent compartments to enable a pigeon to be released without interfering with the other pigeons in the container.

A further object is the provision of a collapsible paper board pigeon container having portions constructed to securely hold the container in a box-like shape.

A further object is the provision of a blank for forming a collapsible pigeon container.

These and other objects are attained by the novel construction hereinafter described and illustrated in the accompanying drawing, forming a part hereof, and in which:

Figure 1 a plan view of a blank embodying the invention.

Figure 2 is a perspective of a container embodying the invention.

Figure 3 is a sectional view taken on the line 3—3 of Figure 2.

Figure 4 is a sectional view taken on the line 4—4 of Figure 2.

Figure 5 is a perspective view of one end of the container partially open.

Referring to the drawing in Figure 1 is shown a blank, preferably of cardboard or similar material, for forming a collapsible container especially adapted for the transportation of carrier pigeons. The blank comprises four sections 1, 2, 3, 4, of equal width, separated by scored lines so that they can be folded relatively to each other.

Section 1 has flaps 5 at each end thereof extending outwardly a distance substantially equal

to the width of section 1. Scored lines 20 enable the flaps 5 to be folded relative to section 1. Integral with and cut from flap 5 is a tongue 6 having a portion extending beyond the outermost edge of flap 5. Scored line 7 enables the tongue 6 to be bent intermediate its length, and scored line 8 enables the tongue to be folded relative to flap 5.

Section 2 and 3 are provided at the ends thereof with tabs 9, which can be folded by means of scored lines 21. Section 4 also has at the ends thereof tabs 10 which can be folded by means of scored lines 22. The tabs 10 have cut-out portions 11 at the edges thereof, and adjacent its junction with section 4 tab 10 is provided with a slit 12 slightly outward from the scored lines 22. Short slits 13 at the ends of slit 12 traverse the scored lines 22. The slit 12 is of sufficient width to receive the tongue 6 up to the scored line 7.

Section 3 is also provided along its longitudinal edge with a tab 14, which can be folded by means of scored line 24. Flaps 5 are provided with apertures 18, and sections 2 and 3 are provided with square apertures 15 diagonally arranged. Section 4 has two spaced parallel longitudinal apertures arranged so that the portion 17 between the apertures 16 can serve as a handle.

To form the container, the sections are folded along the scored lines 24, 25, 26, 27 to form a hollow prism, and the tab 14 is secured to section 1 by means of staples or other suitable means.

For shipping purposes, the containers can be collapsed after tab 14 has been stapled to section 1. When so collapsed section 4 will lie flat against section 3, and section 2 will lie flat against section 1.

The containers are shipped in a collapsed condition to the depot for loading the pigeons. At this depot, the containers urged to the box-like form, and tabs 9 are folded so that they form supports between sections 1 and 2, and flaps 5 are folded upwardly with tongue 6 passing over the edge 11 of tab 10 and inserted through the slit 12. This structure locks the sections securely together and provides a rugged, lightweight and stable container for the safe transport of pigeons.

The containers are designed for the transport of two pigeons, and consequently is divided into two distinct compartments by placing in the container a diagonally arranged partition 19. It will be seen that this arrangement enables the removal of one pigeon without disturbing the other pigeon. The apertures 15 enable messages to be secured to a pigeon without removing the pigeon

from the container, and the apertures 8 and 16 are for ventilation.

From the above description it will be seen that there has been provided an effective and simple container for the safe transport of pigeons. The container is expendable since it is preferably made of cardboard or the like, and is inexpensive to manufacture. While the container has been described above in connection with the transport of pigeons, it is obvious that the locking means for securing the sections together can be effectively applied in the formation of containers for other purposes.

The above description is to be considered as illustrative and not limitative of the invention of which modification can be made without departing from the spirit and scope of the appended claims.

The invention having been described, what is claimed is:

1. A blank for forming a collapsible container comprising a bottom section a top section and two side sections, said sections being rectangular and separated by scored lines so that they can be folded relative to each other, square flaps extending from the bottom section and separated therefrom by scored lines, tongues projecting from the flaps and provided with scored lines so that the tongues can be folded relative to the flaps and also folded intermediate their length, tabs extending from the ends of the top section and separated therefrom by scored lines, said tabs having cut-out portions at their free edges and slits adjacent their connection to the top section to receive the tongues, tabs extending from the ends of the side sections and separated therefrom by scored lines, and a tab extending from the side of one of the side sections and separated therefrom by scored lines.

2. A blank for forming a collapsible container

comprising, a bottom section, a top section and two side sections, said sections being rectangular, flaps extending from the ends of the bottom section, tongues projecting from the flaps and provided with scored lines so that they can be folded relative to the flaps and also folded intermediate their length, tabs extending from the ends of the top section having cut-out portions at their free ends substantially the width of the tongues, said tabs having slits arranged to receive said tongues, tabs extending from the ends of the side sections, and a tab extending from the side of one of the side sections, said sections and tabs being separated by scored lines so that they can be folded relative to each other.

3. A blank for forming a collapsible container, comprising a bottom section, a top section and two side sections, said sections being rectangular and separated by scored lines so that they can be folded relative to each other, square flaps extending from the bottom section and separated therefrom by scored lines, tongues projecting from the flaps and provided with the scored lines so that the tongues can be folded relative to the flaps and also folded intermediate their length, tabs extending from the ends of the top section and separated therefrom by scored lines and having cut-out portions substantially the width of the tongues, said tabs having slits adjacent to and parallel with the scored lines connecting the tabs to the top section and other slits at the ends of the last mentioned slits and at right angles thereto, said slits being adapted to receive the tongues, tabs extending from the ends of the side sections and separated therefrom by scored lines, and a tab extending from the side of one of the side sections and separated therefrom by scored lines.
